SUCTION BOX VACUUM CONNECTION
Frederick R. Erbach, Beloit, Wis., assignor to Beloit Corporation, Beloit, Wis., a corporation of Wisconsin
Filed May 8, 1963, Ser. No. 278,890
3 Claims. (Cl. 162—363)

This invention relates to improvements in paper making machines and is more particularly concerned with the suction box of a paper making machine, dewatering the paper stock as it is flowed along the forming wire of a Fourdrinier machine.

A principal object of the present invention is to improve upon the suction boxes heretofore used in Fourdrinier types of paper machines by simplifying the connection of the suction box to its suction and drain connection and by so arranging the connection as to be readily detachable.

Another object of the invention is to provide a suction box for a paper making machine having a simple and improved form of positive quick detachable connection between the suction box and its vacuum and drain connection, enabling the box to be readily removed for cleaning or reworking.

Still another object of the invention is to provide an improved form of paper making machine including a suction box and an air tight quick detachable connection between the suction box and its suction and drain connection, operating on the clamping principle and hanging a connector connected with the suction and drain connection to the suction fitting leading from the suction box.

These and other objects of the invention will appear from time to time as the following specification proceeds and with reference to the accompanying drawings wherein:

FIGURE 1 is a diagrammatic side elevational view of a paper making machine embodying a suction box constructed in accordance with the principles of the present invention;

FIGURE 2 is a fragmentary transverse sectional view of a part of a paper machine with parts removed, and showing the connection from the suction box to the vacuum and drain connection of the machine;

FIGURE 3 is an enlarged detail view of the suction box illustrating the details of the quick detachable connection for connecting the suction box to its vacuum and drain connection;

FIGURE 4 is an end view of the fitting leading from the suction box; and

FIGURE 5 is an end view of the connector connecting the fitting to the vacuum and drain connector, drawn to a reduced scale and looking at the end of the connector adapted to abut the fitting.

In the embodiment of the invention illustrated in the drawings, I have diagrammatically shown in FIGURE 1 a paper machine of the Fourdrinier type and indicated generally by a reference character 10. The paper machine 10 generally comprises a looped forming wire 11 trained about and over a breast roll 12, along and over table rolls 13, a suction box 15, a couch roll 16, a direction changing roll 17 and return rolls 18, 18. Stock is deposited on the upper run of the wire 11 from a head box 19 onto a forming board 20 to form a web which is removed from the wire 11 by a pick up felt 22 urged against the web by a suction pick up roll 21.

The suction box 15, as shown in FIGURE 2 comprises a generally rectangular trough-like body 23 opening along its top and having a perforate top or cover member 24 extending therealong and accommodating the removal of water from the web through the perforations of said

cover (not shown) in a conventional manner. The perforate cover 24 may be made from wood (maple or mahogany), metal, rubber, or a phenolic resin and the cover is perforated with sufficient openings to allow suction to be applied to the underside of the web.

The back side of the suction box is piped to a vacuum pump (not shown) connected with vacuum lines 26 and 27 under the control of conventional regulator valves 29 and 30. Water removed from the web may drain through a drain pipe 31 having the vacuum line 27 extending from the upper end thereof and having a fitting 32 supported thereon and extending at right angles with respect thereto. A level of water is established in the pipe 31 to allow water to drain downwardly along said drain pipe and to prevent the short circuiting of vacuum from the suction box, in a manner well known to those skilled in the art and no part of the present invention, so not herein shown or described.

The fitting 32 has a hose 33 extending along and clamped to its inlet end by a hose clamp 35. The hose in turn extends along the discharge end portion of a connector 36 and is clamped thereto as by a hose clamp 34. The connector 36 in turn has fluid communication with a fitting 37 leading from the back side of the suction box 15.

Referring now in particular to the quick detachable self-sealing connection between the fitting 37 and the connector 36, the fitting 37 is shown in FIGURE 4 as having a passageway 38 leading therewith and terminating into a rectangular outlet opening 39. The outlet opening 39 opens through a widened plate portion 42 having a relatively wide rectangular bearing surface or face 40 extending about the outlet 39 and projecting above and to opposite sides of said outlet. The top of the plate portion 42 has a beveled surface 41 leading inwardly and downwardly from the face 40 toward the body of the fitting and extending for the length of the face 40 at an acute angle with respect thereto. The face 40, with the beveled surface 41, forms in effect a tongue. The face 40 terminates at its lower opposite end portions on opposite sides of the outlet 39 into beveled surfaces 43, 43 extending parallel to the beveled surface 41 and engaged by clamping members 44 hooking along the back of the plate portion, as will hereinafter more clearly appear as this specification proceeds.

The connector 36 has an inlet opening 45, generally rectangular in form of the same size and conforming to the form of the outlet opening 39 leading from the fitting 37. The inlet opening 45 opens through a plate portion 48 and is surrounded by a flat outer vertical bearing surface or face 46 extending about and upwardly of the inlet opening 45. A flange 46a extends along the top of the plate portion 48 perpendicular to the flat face 46 and outwardly of said flat face and has a downwardly opening groove 47 formed therein. One of the faces of said groove is coextensive with said flat vertical face 46. Another face 48a of said groove extends at an acute angle with respect to said vertical face parallel to the angle of the beveled surface 41 when the faces 40 and 46 are in engagement with each other. The downwardly opening groove 47 of the connector 36 may thus be hooked over the beveled surface 41 of the fitting 37 and the overhanging weight of the fitting 37 will maintain the faces 40 and 46 in engagement with each other when connecting the connector 36 to the fitting 37. The faces 40 and 46 may be finished by machining and grinding to provide an accurate abutting joint between said faces and to thereby prevent the leakage of air at the joint between the fitting 37 and the connector 36, when the faces 40 and 46 are clamped together.

Beveled surfaces 49 parallel to the beveled surface 48 extend angularly inwardly from the lower marginal por-

tions of the face 46 at opposite sides of the passageway 45 to provide clearance for the clamping members 44.

The connector 36 has inclined bosses 50 spaced from the plate portion 48 and projecting from opposite sides thereof at the upper end portion thereof and drilled at 5 the angle of the faces 41 and 43 to slidably receive the clamping members 44.

The clamping members 44 are mounted in associated bosses 50 to extend at the angle of the faces 43. Each clamping member 43 has a hook-like lower end portion 51 having a generally V-shaped notch 52 extending therealong, the faces of which conform to the back of the plate portions 42 and the beveled face 43. The clamping members 44 are translationally moved along the bosses 50 as by nuts 55 threaded on the outer end portions 15 thereof and abutting washers 56 having abutting engagement with the outer end portions of the bosses 50.

In assembling the connector 36 to the fitting 37, assuming the clamping members are loosely carried in the bosses 49, the connector 36 is first suspended on the 20 tongue formed by the beveled surface 41 and front face 40 by engagement of the grooved portion of said connector with said beveled surface or tongue. The overhanging weight of the connector 36 will then bring the faces 40 and 45 into abutting engagement with each 25 other. The clamping members 44 may then be hooked onto the opposite lower end portions of the plate portion 42 to extend parallel to the faces 43. The nuts 55 may then be turned along the threaded portions of the clamping members 44, to bring the tongue at the apex between 30 the faces 40 and 41 into tight engagement with the groove 47 and to pivot the connector 36 about the apex and bring the faces 40 and 41 into tight engagement with each other to form a positive leakproof connection between the fitting 37 and connector 36.

When it is desired to remove the connector 36 from the fitting 37, it is merely necessary to loosen the nuts 55 from the clamping members 44 and release the notches 52 from the apex between the lower end portions of the faces 42 and then lift the connector 36 from the fitting 37.

It may be seen from the foregoing that a simple quick detachable connection has been provided between the fitting 37 and the connector 36 connecting the suction box 15 to a source of vacuum and accommodating ready removal of the connector for cleaning of the suction box or 45 reworking of the cover thereof.

It may further be seen that in addition to its simplicity, the joint between the abutting surfaces of the connector 36 and fitting 37 is air tight and is maintained air-tight by a few turns of the nuts 55, retaining the connector in assembled relation with respect to the fitting and increasing the tightness of the joint between the faces 40 and 46 as said nuts are turned in a tightening direction.

While I have herein shown and described one form in which the invention may be embodied, it may readily be 55 understood that various variations and modifications in the invention may be attained without departing from the spirit and scope of the novel concepts thereof.

I claim as my invention:

1. In a paper machine including a suction box having 60 a perforate cover along which the Fourdrinier wire travels, means connecting said suction box with a source of vacuum to effect the drawing of water from a web on said wire, comprising

a fitting member leading from said suction box having a passageway extending therealong and opening to the outer end thereof,

said fitting member having a plate portion through which said passageway leads and having a flat vertical bearing face extending about and above said passageway,

a beveled surface leading inwardly and downwardly of said flat bearing face at an acute angle with respect thereto,

a connector having a passageway leading therealong opening to opposite ends thereof and registrable with said passageway leading along said fitting member,

said connector having a flat bearing face extending about the inlet end of said passageway and adapted to engage said flat bearing face of said fitting member,

a flange extending perpendicular of said flat bearing face of said connector along the upper end of said flat bearing face and outwardly therefrom,

a downwardly opening groove formed in said flange having one face coextensive with said flat bearing face and a second face inclined outwardly with respect to said flat bearing face at an acute angle with respect thereto and engageable with the beveled surface of said fitting member and supporting said connector on said fitting member,

and clamping members connected between the lower end portion of said fitting member and the upper end portion of said connector and extending at the angle of said beveled surface of said fitting member and said inclined face of said groove and clamping said flat bearing faces in engagement with each other and exerting pressure on said fitting member and connector to force said groove into tight engagement with said inclined beveled surface of said fitting and maintain said flat bearing faces in leakproof engagement with each other.

2. In a paper machine including a suction box having a perforate cover along which the Fourdrinier wire travels,

means connecting said suction box with a source of vacuum to effect the drawing of water from the web on said wire through said perforate cover, comprising

a fitting member leading from said suction box and having a passageway extending therealong and an opening to the outer end thereof, said fitting member having an outer plate portion through which said passageway opens, said outer plate portion having a plane outer vertical face extending about said passageway and projecting upwardly of said passageway and having a beveled surface inclined downwardly and inwardly from the upper end thereof and with said flat face forming a tongue extending across said passageway,

a connector having a passageway extending therealong and opening to opposite ends thereof and having a flat bearing face extending about said passageway for engagement with said flat bearing face of said fitting member,

said flat bearing face terminating at its upper end in a flange extending therealong perpendicular thereto and outwardly of said flat bearing face of said connector,

said flange having a downwardly opening groove formed therein, one face of which is coextensive with said flat bearing face and the other of which is inclined outwardly with respect to said flat bearing face at an acute angle,

said downwardly opening groove being adapted to hook onto said tongue, and the overhanging weight of said connector bringing said flat faces of said fitting and said connector into engagement with each other,

said plate portion of said fitting member having an inclined lower end portion parallel to the upper beveled surface of said plate portion, and clamping members engaging said inclined face of said fitting member and hooking onto said

fitting member at the lower rear end portions of said beveled faces and extending parallel to said beveled faces and having takeup connection with said connector.

3. A paper machine in accordance with claim 2
wherein lugs spaced along said connector from the flat bearing face thereof extend laterally from opposite sides thereof and having apertured portions extending at the angle of said inclined face of said groove and parallel thereto,
wherein clamping members slidably extend through the apertured portions of said lugs and have upwardly opening hook-like lower end portions extending along and hooked to the beveled faces at the lower end of said plate portion,
and wherein nuts threaded on said clamping members and engaging said lugs bring said flat faces of said

fitting member and said connector into compressive engagement with each other.
